US0D1071685S

(12) **United States Design Patent** (10) Patent No.: **US D1,071,685 S**
(45) Date of Patent: ** Apr. 22, 2025

(54) **SCISSORS**

(71) Applicant: **KAI R&D CENTER CO., LTD.**, Gifu (JP)

(72) Inventors: **Akira Abo**, Seki (JP); **Katsumi Hasegawa**, Seki (JP); **Jun Otsuka**, Seki (JP); **Nobuki Hizume**, Seki (JP)

(**) Term: **15 Years**

(21) Appl. No.: **35/520,757**

(22) Filed: **Apr. 28, 2023**

(80) **Hague Agreement Data**

Int. Filing Date: **Apr. 28, 2023**

Int. Reg. No.: **DM/229096**

Int. Reg. Date: **Apr. 28, 2023**

Int. Reg. Pub. Date: **May 3, 2024**

(30) **Foreign Application Priority Data**

Nov. 7, 2022 (JP) ..... 2022-024079 D

(51) LOC (15) Cl. **08-03**

(52) U.S. Cl.

USPC **D8/57**

(58) **Field of Classification Search**

USPC D8/51-58

CPC B26B 13/20; B25G 1/102

See application file for complete search history.

Primary Examiner — Deanna L Pratt

(57) **CLAIM**

The ornamental design for scissors as shown and described.

DESCRIPTION

1. Scissors

1.1: Perspective

1.2: Front

1.3: Back

1.4: Top

1.5: Bottom

1.6: Left

1.7: Right

The evenly spaced broken lines illustrate portions of the scissors that form no part of the claimed design. The dotted-dashed lines illustrate the boundary between the claimed and unclaimed subject matter and form no part of the claimed design.

1 Claim, 7 Drawing Sheets
